UNITED STATES PATENT OFFICE.

DAVID H. STEWART, OF PITTSBURG, PENNSYLVANIA.

NEWSPAPER-VENDING MACHINE.

No. 859,853.

Specification of Letters Patent.

Patented July 9, 1907.

Application filed June 22, 1906. Serial No. 322,850.

To all whom it may concern:

Be it known that I, DAVID H. STEWART, residing at Pittsburg, in the county of Allegheny and State of Pennsylvania, have invented a certain new and 5 useful Newspaper-Vending Machine, of which the following is a specification.

This invention, which relates generally to improvements in that type of coin released vending machines for selling newspapers, magazines and the like, more 10 particularly seeks to provide a machine of this type especially adapted for outdoor use, such for example, as depots, suburban railway stations, hotels and other public places, of a simple and inexpensive character in which the co-operative parts are especially 15 designed for positively ejecting a single paper or article to be vended at a time and having such adjustment whereby they can be quickly set for discharging the ordinary weekly form or the heavy Sunday or extra forms of newspapers.

20 My invention also comprehends an improved construction of vending machine having ejecting mechanism and actuating means therefor, so arranged that only a single paper can be fed out at each operation, in which is included a follower or presser means that 25 engages the bulk or package of papers contained in the machine in full contact with each other and in such manner whereby the frictional contact of the several papers in the pack is reduced to the minimum and the position of all the remaining papers in the 30 pack is not disturbed by the foremost one of the papers as it is being fed from the machine to the purchaser.

This invention also comprehends a means for sustaining the papers in a package or bulk, ends up, a carriage for positively feeding the bulk toward the 35 discharging slot, a means for gripping the lower end of the outermost one of the papers in the pack, a coin released mechanism permitting an operation of the paper gripping means, in which is included devices for controlling the movement of the paper gripping 40 means, whereby to provide for a predetermined thrust or action of the lever operated by the buyer and for controlling the coin slot to prevent insertion of a coin until after a paper has been fed out and the delivery mechanism has resumed a normal position.

45 In its more subordinate features, my invention consists in certain details of construction and peculiar combination of parts, all of which will hereinafter be fully described, pointed out in the appended claims and illustrated in the drawings in which:—

50 Figure 1, is a perspective view illustrating my invention as set up for use. Fig. 2, is a longitudinal section thereof, the pressing carriage or follower being held back to its inoperative position, and the top thrown back to admit the placing of a stack of papers 55 into the receiving compartment. Fig. 3, is a similar view, the carriage or follower being in its operative

position and the delivery mechanism shown in the act of discharging a paper. Fig. 4, is a horizontal section of my vending machine taken substantially on the line 4—4 on Fig. 3. Fig. 5, is a transverse section of the same taken just in advance of the delivery roller. Fig. 6, is a detail vertical section which illustrates the correlation of the discharging roller, the presser and loose follower member and the manner in which the paper is delivered into the discharging channel or guideway. Fig. 7, is a detail cross section taken substantially on the line 7—7 on Fig. 9, which shows the normal position of the detent for locking the delivery mechanism from action. Fig. 8, is a similar view showing the pusher device actuated 70 to engage the coin for releasing the pawl from the delivery roll. Fig. 9, is a horizontal section of the coin actuating mechanism. Fig. 10, is a transverse section thereof on the line 10—10 on Fig. 7. Fig. 11, is a detail plan view of the presser member 20 and the 75 combined pull and lock member 26—27, and Fig. 12, is a transverse section thereof.

In the practical arrangement of my invention, I provide an external housing of suitable ornamental shape, which may be made up of heavy sheet metal or 80 light castings, and if desired, the front wall shaped for containing advertisements or other descriptive matter, and when used for suburban places, may form a convenient space for train time tables, etc.

At the lower edge the front has a delivery slot that 85 extends nearly the full width thereof and is sufficiently wide to permit of the discharge of daily and weekly papers when folded, it being understood that when utilized for selling magazines and like bulky matter, the shape of the casing and the delivery slot are proportioned accordingly.

The casing is provided with a vertically disposed compartment 2, adapted to receive the papers in bulk which is normally closed by a hinged and locked cover 3. The bottom 4 of the said compartment is mounted on suitable guides for a limited longitudinal adjustment, which is effected by the adjusting screws 5—5 mounted on the rear end of the casing, see Fig. 2, in such manner that by feeding them inwardly or outwardly, the front end of the said bottom 4 can be set 10 relatively to the front vertically disposed wall 6 of the compartment and the feed roller presently referred to, whereby to widen or restrict the outlet throat 7 from the compartment to suit the differences in thickness of the usual folded daily papers and the heavy Sunday 10: or extra issues.

By referring now more particularly to Figs. 2 and 3 it will be noticed the lower end of the front wall 6 does not extend down to the plane of the bottom 4 whereby to provide transverse space between the said bottom 11: end of the wall and the adjustable bottom 4 to receive the feed roller 8, which, in the practical construction,

may consist of a core of wood or may be cast metal, and this roller 8 has end spindles suitably mounted in bearings in the casing sides and one of which extends outside of the casing to receive an actuating crank handle 5 10 as clearly shown.

The roller 8, which is of the full width of the paper holding compartment, has a flexible covering 80, such, for example, as thick rubber belting which is fixedly mounted on the core and the said covering carries 10 picker spurs or brads 11 that are driven through the belting from the underside to project sufficiently beyond the perimeter of the roller to prick the papers sufficiently to pull them down without danger of tearing or appreciably mutilating them.

15 As shown, the roller is projected with its upper rear edge into the lower front end of the paper compartment to engage with the outermost one of the pack of papers, to pull it down through the discharge throat, the width of which as before stated, is governed to suit 20 the thickness of the papers to be sold by adjusting the bottom plate 4, and the said throat at the lower edge has a transverse friction roller bearing member 12 that opposes the delivery roller 8 and discharges onto a smooth downwardly inclined slide board 13 that leads 25 the paper down to the discharge slot 1 and to provide for a proper feeding of the paper after it has been started down by the delivery roller, the front wall of the paper compartment is faced with a smooth metal plate that extends down over the paper impinging face of the 30 roller at which point it is formed with a series of slots 15 for the passage of the pins on the roller, as best shown in Fig. 5, by reference to which it will be also seen the slotted end of the plate extends diagonally downward parallel with the guide or slide board 13 to the discharge 35 slot 1.

By arranging the several parts just described, in the manner stated, frictional resistance on the paper after it has been started down by the delivery roller is reduced to the minimum and danger of tearing or mutilating the paper is positively overcome since each 40 longitudinal row of teeth or prongs on the roller engage the paper for a short period only, since the paper is continually drawn off the spurs by reason of its deflection by the slotted face plate.

45 Heretofore in the practical experiment with vending machines in which the papers are fed forward to a delivery means, adapted to grip the forward paper and in which the papers are being fed to the delivery mechanism and held in a vertical plane ends up and 50 in which a follower or presser means held to engage with practically the entire rear or back face of the paper bulk and in which the pull on the papers has been at the lower or upper edge only, it has been demonstrated that it is impossible by reason of the frictional 55 contact with each other of the large number of papers usually held in bulk, to feed the papers single from off the package or bulk, or without danger of tearing and mutilating the same and also choking up the feed devices, rendering the machines unreliable and frequent 60 loss of the price of the paper to those desiring to obtain them. In my invention I have especially provided for overcoming this serious objection in the use of newspaper vending machine in that I feed the papers and hold them in such position relatively to the 65 delivery mechanism that a miss in delivery is almost

impossible and the delivery of more than one paper at a time or the choking up of the machine is absolutely avoided. For such purpose I provide a follower means operating under spring pressure arranged to effect a positive compression on the paper bulk only at that 70 point where the delivery roll engages the same and a light and flexible pressure of the remaining portion of the paper bulk sufficient to only sustain the said bulk of papers in a proper vertical position.

The follower mechanism is in the nature of a cross bar 20 of the full width of the paper compartment which is held to slide over the bottom plate 4 and whose pressure opposes, or in other words, is directly against that part of the delivery roll that projects into the lower front end of the paper compartment, and a flexible 80 metal plate 21 that is fixedly connected to the front end of the bar 20 and projects vertically therefrom so as to lightly rest, under a flexible spring pressure, against the upper part of the pack of papers whereby to sustain the said upper parts of the papers in loose contact with each 85 other and in such manner that so far as the upper portion of the papers are concerned there is practically no frictional resistance thereby exerted against the front paper as it is being pulled down by the delivery roll.

The cross bar is held pressed forward against the lower 90 end of the paper pack by a pair of stout coil springs 22—22 disposed one at each side of the casing, which are made fast at their lower ends to cords connected to the cross bar or follower and which take around guide pulleys 25—25 on the front end of the machine as clearly 95 shown in Fig. 2.

For conveniently pulling back the follower and holding it back during the operation of filling the paper compartment, the same has a handle 26 and dogs 27—27 which engage holding lugs 28—28 that are secured to the 100 bottom 4 of the casing, as shown.

So far as described, the manner in which my apparatus is used is best explained as follows: To put it in condition for vending, the operator unlocks and swings back the cover which opens the top and back of the 105 casing sufficient to enable him to pull back the pressure follower and lock it to its back position. The bulk of papers which have been previously properly folded are dropped with their folded edges down, into the holding compartment and shoved up against the front 110 wall of said compartment to bring the foremost paper in position to be engaged by the delivery roller, after which the follower is released so it moves up against the rear end of the paper bulk and the cover is then swung down locked. By giving the roller a rotation or quick 115 forward rotary action, which is done by manipulation of the crank handle, the roller engages the front paper and pulls it down through the discharge throat and slot, see Fig. 5, it being understood that in the adjustment of my machine, the circumference of the roller is 120 substantially equal the length of the folded paper to be discharged, thus providing for a substantially continuous grip on the paper its entire length during the act of discharging, although that is not necessary since a quick rotary motion of the roller will pull the paper down so it projects beyond the discharging slot from whence, if desired, it may be pulled out by hand.

Since my machine is more particularly intended for use in public and exposed places, means must be provided for bringing the delivery mechanism into a 130

proper normal position to insure a proper subsequent operation, to provide against the same readily getting out of order or from being disorganized by tampering, from turning the roller backward and also for permitting the movement thereof only after the proper token has been deposited to pay for the paper.

A backward movement of the feed roller is prevented by means of a ratchet disk 30 mounted on the rim of the said roller with which engages the stop pawl 31, as clearly shown in Figs. 8 and 10, by reference to which it will be seen that the said ratchet has a locking collar 32 provided with a single locking notch 33 in its peripheral edge which is so disposed relatively to the crank handle so that when the crank handle is turned to zero or its normal position, the said notch will register with a spring actuated detent 34 pivotally mounted on a bracket 35 and provided with a heel portion 36 that projects over the discharge end of the coin chute 37 which extends up to and is adapted to receive the coin when it is inserted through the coin slot 37^a formed at the top side of the casing above the crank handle.

39 indicates a pull bar, spring held to its inner or normal position, which slides in suitable guides and is provided with a slot that forms a pocket 40 and which is freely movable in the space between the heel of the locking detent and the discharge end of the coin chute and is so arranged that when a coin is dropped into the slot the coin will enter the pocket in the puller and rest upon the heel of the detent.

30 Adjacent to the discharge end of the coin slot is an inclined abutment 41 which is so arranged relatively to the coin slot, the pull bar and the locking detent, that when the said pull bar is drawn outwardly, the coin will engage the said abutment and be deflected downwardly sufficient to depress the heel end of the detent to lift its other end out of a locked engagement with the locking collar 32 held to turn with the delivery roller and the said collar, as will be noticed by reference to Figs. 7 and 8, is provided with a cam lug 32^a which, the instant that the delivery roller begins to rotate, engages a pawl on the pull bar, forces said bar further outward whereby to discharge the coin from the pocket in the pull bar, thereby releasing the said pull bar and permitting it to be returned to its normal and inwardly set position which is done through the medium of the spring 44, and the pull bar has its finger member slidably connected with the other or coin holding end of said bar, and said finger member has a collar 45^a to limit the outward pull of the pull bar under finger action so that the coin is not dropped until after the delivery roller has been started, when the cam lug thereon finishes the outward thrust of the pull bar and causes the coin to be dropped from the heel end of the detent.

55 The pull bar projects through the side of the casing and has a thumb piece 46 for being gripped by the operator when he grasps the crank handle, whereby to draw the said pull bar outward.

The proper adjustment of the mechanism, so the same will deliver a paper, is designated by a suitable indicator plate on the outside of the casing which has a zero mark. When the crank handle is down in line with the said zero mark, to obtain a paper, it is only necessary to drop the coin in the slot, then with the thumb,

to draw out the pull or coin controlling bar whereby 65 to trip the detent 34, and then to turn the crank handle in the direction indicated by the arrow on Fig. 1.

47 designates a plate which acts as a gate to close the coin slot and the said plate is movable inside the coin casing and is pivotally mounted on the bracket 35 70 and is normally forced outwardly, through the medium of the spring 49, which carries a pendent heel 50 that engages with an annular cam flange 51, mounted on the core of the delivery roller and which extends nearly to a complete circle and terminates just in advance of 75 the locking notch with which the locking detent engages, such arrangement of parts serving to maintain the locking gate to close the slot during the complete rotation of the crank handle.

It will be manifest, by reference to the drawings, 80 particularly Figs. 7 and 8, that by reason of the coin mechanism just described, that should the operator, by giving a quick, partial rotation to the delivery roller and not bring the crank handle to the normal or zero point, that the slot will remain closed and therefore the 85 machine cannot be operated again until the crank handle has been turned to complete its rotation and brought to the zero point, at which time the locking detent has again engaged the locking notch and the delivery roller is thereby held from being further actuated until the 90 proper coin has been inserted in the coin slot.

In the drawings, I have shown a locking detent, a pull bar and the discharge end of the coin slot, relatively so arranged, that the machine can be operated by a single coin which may be a penny or a nickel but 95 it is manifest that if the machine is intended to sell a paper of the value of two cents or a magazine of the value of ten cents, that the said parts can be readily modified so that it will require the insertion of two pennies or two nickels, one after the other, so that the 100 two will rest and form a link between the heel of the locking detent and the abutment adjacent the lower end of the coin slot, it being also understood that when thus arranged, the pocket in the pull bar is made of sufficient depth to properly hold the two coins, edge 105 to edge, in a vertical plane.

From the foregoing description, taken in connection with the accompanying drawings, it is believed the complete construction and manner of operation of my invention will be readily understood.

It will be observed that under normal conditions the delivery roller cannot be actuated but should at a previous operation, the crank handle not having been turned sufficiently to reach the normal or zero point, it can be turned finally only sufficient to reach the zero 115 point and which would not be ample to feed down the paper so that the same could be withdrawn from the discharge slot, since the discharge slot 1 is a considerable distance away from the throat from which the papers are fed by the delivery roller. Again, the 120 roller is positively held from being turned backward, thereby preventing, by reason of tampering with the machine, the clogging of the discharge throat and since the coin slot remains closed until the crank handle has been turned to the normal or zero point, the purchaser 125 cannot lose his coin by reason of the slot being open and delivering mechanism not being in proper position to receive the same to deliver the paper in return therefor.

While the specific means shown, the spring detent 34, illustrates a simple and inexpensive device for locking the roller 8 from rotation, I desire it understood that I do not limit myself to such detent devices, since the same may be readily modified or varied without departing from the scope of the appended claims.

Having thus described my invention, what I claim and desire to secure by Letters Patent, is:—

1. In a vending machine, a receptacle for holding the papers in bulk, having a discharge throat that extends down below the lower front end of the said receptacle, the receptacle including an adjustable bottom having a roller bearing at the front end below the axial line of the feed roller, the face plate on the front walls of the receptacle having a bottom extension that forms the top wall of the discharge throat, said plate having vertical slots in line with the bottom of the receptacle, the feed roller axially journaled in the horizontal plane above the bottom of the receptacle and in front of the face plate, said roller having fingers that project through the slots in the face plate and a presser device for forcing the lower face of the papers against the roller fingers, all being arranged substantially as shown and described.
2. In a vending machine of the character described, in combination with a delivery mechanism arranged to grip the outermost one of a series or pack of papers at the lower end thereof; of a presser follower comprising a solid lower portion that exerts pressure against the paper pack in line with the delivery mechanisms and a flexible upper portion that flexibly sustains the upper end of the paper pack in a vertical position.
3. In combination with the casing having a compartment to receive the papers in series and to sustain them in a vertical position on their folded ends, a discharging throat at the lower front end of the compartment, a de-

livery roll mounted in front of the discharge throat and having its peripheral face movable through said throat to engage with the outermost one of the papers; of a presser follower comprising a transverse bar movable over the bottom of the paper compartment against the lower part 40 of the back of the paper bulk, spring and cable connections joined with the said cross bar for normally forcing the bar forward and a means for holding the bar locked to its rearmost position, for the purposes specified.

4. In a vending machine of the character described, the 45 combination with the paper holding compartment, adapted to receive the bulk of papers, end up, said compartment having a discharge at its front end, the casing having a delivery slot, a chute that extends from the throat to the slot, a delivery roller having transverse rows of peripheral spurs, that project through the throat, a face plate that extends down over the front of the discharge throat and extends parallel with the chute to the delivery slot, said plate having slots through which the roller spurs project, and a means for rotating the roller, as set forth.

5. A newspaper vending machine having a compartment for receiving a series of papers in bulk and in a vertical position, said compartment having a discharge at the lower front end, a spur roller mounted in front of the throat, having a series of projecting fingers, a slotted guard plate 50 located between the roller and the papers and having slots for the fingers of the rollers to project through, whereby to engage the outermost one of the series of papers held in the receptacle, and a presser follower that engages the lower end of a series of papers, said follower having movement in the horizontal plane and in axial alignment with the feed roller.
